UNITED STATES PATENT OFFICE

172,843

COMBINED WALL PLAQUE AND CONDIMENTS SHAKER UNIT

Harry Scheer, Chicago, and Joseph A. Hill, Glen
Ellyn, Ill., assignors to Superior Plastics Inc.,
Chicago, Ill., a corporation of Illinois

Application February 19, 1954, Serial No. 29,107

Term of patent 14 years

(Cl. D44--22)

To all whom it may concern:

Be it known that we, Harry Scheer and Joseph A. Hill, citizens of the United States and residents of Chicago, county of Cook and State of Illinois, and Glen Ellyn, county of Du Page, and State of Illinois, respectively, have invented a new, original, and ornamental Design for a Combined Wall Plaque and Condiment Shaker Unit, of which the following is a specification, reference being had to the accompanying drawing, forming part thereof.

Fig. 1 is a top plan view of a combined wall plaque and condiment shaker unit, showing our new design;

Fig. 2 is a front elevational view thereof;

Fig. 3 is a side elevational view thereof; and
Fig. 4 is a bottom plan view thereof.

We claim:

The ornamental design for a combined wall plaque and condiment shaker unit, substantially as shown.
